UNITED STATES PATENT OFFICE.

ORCENITH F. ALLEN, OF TEMPLE, TEXAS.

BUCKLE.

No. 920,899.

Specification of Letters Patent.

Patented May 11, 1909.

Application filed May 2, 1908. Serial No. 430,506.

To all whom it may concern:

Be it known that I, ORCENITH F. ALLEN, a citizen of the United States, residing at Temple, in the county of Bell and State of Texas, have invented a new and useful 5 Buckle, of which the following is a specification.

This invention relates to buckles, and more particularly to devices of that class in 10 which the two ends of the independent, flexible element transmitting the tensile stress are clasped together by the transverse pressure of a cam.

It is the aim of this invention to provide 15 in a merchantable and inexpensive form, a buckle which shall perform its office quickly, positively and without mutilation of the parts upon which it exercises its function.

With these and other objects in view, as 20 will hereinafter more fully appear, the invention consists in the novel construction and arrangement of parts hereinafter described and claimed.

In the accompanying drawings, Figure 1 25 is a plan view of the device. Fig. 2 is an end elevation. Fig. 3 is a vertical longitudinal section in the plane $x-x$ Fig. 1 with the added detail of the clasped strap-ends, and Fig. 4 is a side elevation of the device 30 in operation upon two strap-ends. Fig. 5 is a perspective detail view of the locking cam.

Similar letters of reference are employed 35 to indicate corresponding parts throughout the several figures of the drawings.

As shown, the device embraces a base portion A, the sides of which, B, are bent downward at right angles to the part A to form the lateral supports for the strap-end C. 40 Superimposed upon the base portion A and parallel thereto, is the member D, having its sides, E, bent downward at right angles to the part D to form a lateral support for the strap-end F, the ends, G, of the member 45 D being prolonged beyond the ends of the part E. Upon the part D and slightly inset from its edges, are the ears H, through which passes the axle I upon which is suspended so as to be rotatable through a determinate arc, the cam J. Attached to the 50 member D, preferably by the rivet K, is the resilient cam rocking member L, brushing with a slight pressure upon the cam J and serving to force it quickly to a firm bearing 55 upon the strap end F. It is to be under-

stood that in the completed device, the parts A, D and H are firmly united by soldering, clenching or other method adapted to that end; or they may be fashioned integrally, wholly or in part.

The cam J may be of any form; preferably, however, as shown, it is substantially ovate-oblong in cross section, this form having been selected as one adapted to attain its position of maximum efficiency 60 with a minimum of lost motion. The axle I is so placed in the cam J that the center of gravity of the cam is below the line of suspension, the end P projecting to form a thumb-lever as hereinbefore described. The 65 bearing surface of the cam J is preferably smooth, that no injury may be inflicted upon the upper or dressed side of the strap F.

The device may be permanently attached 70 to the strap-end C by any of the conventional methods of the art. As shown, it is retained in position by the rivets M, which are passed through the apertures N and brought to a bearing contact by malleation. That portion O of the member A which is 75 beneath the bearing surface of the cam J is provided with transverse teeth Q, one of the terminal ones of which is longer than the remaining ones in order to form a kink or bend in the strap end C and thus accentuate the gripping action of the cam. As 80 will be understood, the teeth referred to engage with the lower or pelt side of the strap end F, as clearly shown in Fig. 3.

In practical operation, the strap-end F is 85 thrust between the cam J and the base member A and drawn tight, being retained against withdrawal by the pressure of the cam J and the friction of the surface O. When it is desired to release the strap, a 90 slight pull upon the protruding end, will loosen the cam J whereupon it may be held clear by thumb pressure upon the end P, and the strap withdrawn.

What is claimed is:—

1. A buckle comprising a base plate provided with lateral strap supports, a top plate provided with lateral strap supports, ears carried by the latter plate, an axle rotatably mounted in the ears, a cam carried by the axle, and a spring having one end secured to the top plate and its other end disposed upon the cam.

2. A buckle comprising a base plate provided with lateral strap supports, a top

plate provided with lateral strap supports, with an orifice, and with outward projecting ears, an axle rotatably mounted in the ears, a cam mounted upon the axle and projecting through the orifice, and a spring having one end secured to the top plate and its other end disposed upon the cam.

In testimony that I claim the foregoing as my own, I have hereto affixed my signature in the presence of two witnesses.

ORCENITH F. ALLEN.
